WORKTABLE WITH ROTARY AND TILTING
ADJUSTMENTS

William O. Gilly, El Cerrito, Calif.

Application February 8, 1946, Serial No. 646,475

1 Claim. (Cl. 311—35)

(Granted under the act of March 3, 1883, as
amended April 30, 1928; 370 O. G. 757)

1

The present invention relates to work tables. Objects of the present invention are to provide an improved work table having a work supporting surface which may be both rotated and tilted; to provide such an improved work table, a work supporting surface of which may be selectively secured in a plurality of adjusted positions; to provide an improved construction and arrangements of elements in a device of the character described and for the purposes set forth; and to accomplish the above objects in a facile, economical and efficient manner.

In accomplishing these and other objects of the present invention, I have provided improved details of structure, the preferred form of which is illustrated in the accompanying drawing, wherein:

Fig. 1 is a plan view of a work table embodying the features of the present invention and having a portion of the stationary table broken away to show the engagement of the disc and its associated latch;

Fig. 2 is a partial view in elevation of a work table embodying features of the present invention; and,

Fig. 3 is a reduced partial view in transverse section showing the engagement of the disc and its associated latch.

Referring more in detail to the drawing:

The stationary table 1, has a U-shaped recess 2, formed therein. Two bearing sockets 3, are mounted on the stationary table on either side of said recess 2, and cooperate to rotatably mount a tubular support or shaft 4, extending across said recess 2. A bearing block 5, is secured to the support 4, at substantially the center of the recess 2. A circular work supporting member 6, having a work supporting surface, is disposed within said recess 2, and rotatably mounted in said bearing block 5, by means of a pintle 7, formed on said work supporting member 6, and journaled in said bearing block 5.

The work supporting member 6, is formed to provide a plurality of notches or interruptions 8, spaced about its periphery. A latch 9, is mounted on the shaft 4, and has a spring 10, associated therewith for urging an arm 11, of the latch 9, into engagement with the member 6. The latch 9, is also provided with a remote control, as the foot lever 12, and wire enclosed in a flexible cable represented at 13, for moving the latch 9, out of engagement with the member 6. The arm 11, of the latch 9, is adapted to engage within the notches or interruptions 8, of the work support member 6, and restrain rotation of said member 6, and restrain rotation of said member 6.

6, about an axis perpendicular to said member 6, at its center.

A partial disc 14, is secured to the shaft or support 4, and has notches or interruptions 15, spaced along its arcuate periphery, similar to the notches 8, of member 6. A latch 16, is mounted on the stationary table 1, and urged into engagement with the disc 14, by a spring 17. The latch 16, is also provided with a remote control including a foot lever 18, connected to the latch 16, by a wire enclosed in a flexible cable represented at 19. The latch 16, is adapted to engage within the notches 15, of the partial disc 14, to restrain rotation of the shaft 4, and thereby restrain tilting of the member 6, by preventing said member 6, from rotating about the axis of the shaft 4.

The operation of a work table constructed as above described is as follows:

A work piece (not shown) upon which one or 20 more operations are to be performed is placed upon the work supporting surface of the member 6. It is then adjusted to the position most advantageous, by adjusting the work table. This is accomplished by depressing the foot lever 12, 25 which withdraws the latch 9, from its engagement with the work supporting member 6, thus permitting its free rotation until the foot lever 12, is released at which time the latch 9, is again urged against the member 6, by the action of the 30 spring 10. The member 6, should then be turned until the arm 11, of the latch 9, engages in the nearest notch 8, affording a positive engagement preventing further rotation of said member 6.

The foot lever 18, is then depressed, with 35 drawing the latch 16, from its engagement with the partial disc 14, and permitting the tilting, or rotation of the work supporting member 6 about the axis of the tubular support or shaft 4. The foot lever 18, is then released and the 40 latch 16, is again urged against the partial disc 14, by the action of the spring 17. The member 6, is then rotated a little more in the same direction, or a little in the opposite direction 45 until the latch 16, moves into a notch 15, on the partial disc 14 and thus affords a positive engagement preventing further tilting of the member 6, by restraining rotation of the shaft 4, to which the disc 14, is secured and upon 50 which the work supporting member 6, is mounted by means of the pintle 7, and the bearing block 5.

While I have shown but one embodiment of my invention, it is susceptible to modification without departing from the spirit of the invention. I do not wish, therefore, to be limited by

the disclosures set forth, but only by the scope of the appended claim.

The invention described herein may be manufactured and used by or for the Government of the United States of America for governmental purposes without the payment of any royalties thereon or therefor.

I claim:

A work table of the class described, comprising a stationary table having a U-shaped recess formed therein, a circular adjustable work supporting member received in said recess, said member having a work supporting surface disposed substantially in a plane, and means mounting said member for rotation about an axis perpendicular to said surface and disposed centrally thereof and for rotation about a second axis perpendicular to said axis, said means including a shaft supported in said stationary table and rotatable about said second axis, a partial disc secured to said shaft and having a plurality of interruptions therein, a latch mounted on said stationary table and adapted to selectively engage said disc at said interruptions to maintain said shaft in a plurality of predetermined positions, a bearing block secured to said shaft, a pintle formed on said member and journaled in said bearing block, said pintle mounting said

member for rotation about the first mentioned axis, said member having a plurality of interruptions about its periphery, and a second latch mounted on said shaft and adapted to selectively engage said member at said interruptions and maintain said member in a plurality of predetermined positions.

WILLIAM O. GILLY.
